(57) **CLAIM**

The ornamental design for a glazing tool, as shown.

DESCRIPTION

FIG. 1 is a perspective view of a glazing tool according to the invention.

FIG. 2 is a first side view of the glazing tool.

FIG. 3 is a second side view of the glazing tool.

FIG. 4 is a front view of the glazing tool.

FIG. 5 is a rear view of the glazing tool.

FIG. 6 is a top view of the glazing tool; and,

FIG. 7 is a bottom view of the glazing tool.

The broken lines depict portions of the glazing tool in which the design is embodied that are not considered part of the claimed design.
